LADY'S TRAVELING CASE

Germaine M. Bjorkman, New York, N. Y.

Application November 27, 1936, Serial No. 112,927

4 Claims. (Cl. 190—51)

This invention relates to ladies' traveling or suitcases and has for its main object to provide a case substantially of rectangular shape formed with a sectional or foldable cover or lid, both case and lid being formed with compartments for articles of wear and for toilet articles and the lid being so constructed that upon opening or unfolding of one section thereof, the toilet articles will all be displayed in a position ready for use, 10 while the section of the lid covering the compartment or compartments containing the other articles may remain closed to conceal the latter.

Another object of this invention is to so construct the body and lids that when the section 15 of the lid covering the toilet articles is opened, the case may serve as a dressing table.

Another object of this invention is to provide the section of the lid covering the toilet articles with a mirror, which in the closed position of the 20 said section will extend parallel to the inner face of the latter, but on opening said section will tend to rise into an erect position to be convenient for use.

Another very important object of this invention 25 is to provide a construction that will be comparatively inexpensive and simple.

With these and other objects in view my invention consists in the construction, arrangement and combination of parts as will be hereinafter more fully described and defined in the appended claims.

In the accompanying drawing which constitutes part of this specification and in which similar reference characters denote corresponding 35 parts

Fig. 1 is a perspective view of my novel traveling case;

Fig. 2 is a top plan view thereof;

Fig. 3 is a central vertical cross section, and

40 Fig. 4 is a similar section to Fig. 3, somewhat enlarged, showing a modified detail of the lid portion of the case.

Referring to the drawing more in detail, the case is in form of a substantially rectangular box, 45 of wood or the like, the lower part 10 of which constitutes the body portion and which is divided by longitudinal and transversal partitions 11 and 12, respectively, to form a rear compartment 11^a for the accommodation of articles of wear or the like and front compartments 12^a, 12^b etc. for the accommodation of bottles or similar containers of fluids for toilet use. The upper part or lid 13 is in form of an inverted box and is composed of two sections 13^a, 13^b, of which 50 section 13^a is adapted to serve as a lid for the

rear compartment 11^a and constitutes the main lid, and the section 13^b, serves as an auxiliary lid to close the compartments 12^a, 12^b etc. Of these lid sections, the rear section 13^a is adapted to be hingedly secured to the body 10 as at 13' and the other section 13^b to the main lid 13^a as at 13². In the present embodiment the outer faces of the walls of the body 10 and of those of the lids are suitably covered with cloth, leather or other suitable flexible material, as at 14, so that metal 10 hinges for the lids, 13^a, 13^b to the body 10 and to one another are eliminated. The rear lid 13^a adapted to close the compartment 11^a is provided with a wall 15 projecting inwardly and perpendicularly from the inner face of its top and at a point intermediate the rear wall and partition 11 of the body 10, to form between itself and the rear wall of the lid a compartment 15^a for the accommodation of a roll of tissue paper P or other wiping material for use with cosmetics. It will be seen from Fig. 3 that the pivotal line 20 of attachment between the two lids 13^a, 13^b is located intermediate the rear wall 11' and partition 11. The bottom end of this partition 11 is formed with a ledge 16 extending at a right angle to the latter, forwardly to the partition 11, which when the lid 13^a is closed will bear on the upper edge of said partition and close the compartment 11^a and serve at the same time as a shelf 25 on which can be suitably mounted by means of straps S, or the like, jars, boxes or other receptacles R containing cosmetics or the like.

The side walls of said lid section 13^a are bevelled as at 13³ from the pivotal line 13² downwardly to the front edge of the ledge 16.

The lid section 13^b has no rear wall and the edges 13⁴ of its side walls are correspondingly bevelled, so that when the lid 13^b is in closed position, the abutting bevelled edges of the two lids will bear evenly on one another and the upper faces of said lids will be in perfect alignment with one another and when said lid 13^b is opened or folded over the lid 13^a the bevelled edges 13³ and 13⁴ will be in linear extension of one another. The lower edge of the front wall of said front lid 13^b is adapted when the latter is closed to bear on the upper edge of the front wall of the body 10. Suitable locking means L are provided for locking the lids in closed position.

In the modification shown in Figs. 1 to 3, inclusive, the inner face of the lid 13^b may have suitable means for the attachment of a mirror M, lipsticks and other articles x, y used for make-up.

With the construction hereinabove described

the suitcase, when partly opened, by folding the front lid 13^b over the rear lid 13^a, as shown in Fig. 1, may very conveniently serve as a neatly appearing dressing table, with all articles of 5 toilet, cosmetics etc. being readily displayed for use, while the compartment 11^a holding the wearing apparel or the like is closed by the rear lid 13^a and concealed from view.

In the modification shown in Fig. 4 the mirror 10 M' is shown attached by means of leaf springs 11 to the lid 13^a as at 17^a, in such a manner, that when the lid 13^b is in closed position, the mirror 17 will bear against the inner face of 15 said lid 13^b, but when the latter is unfolded, the mirror will be forced into erect position convenient for use as indicated by dotted lines.

The action of the springs 17 against the lid 13^b will have the effect of lifting the lid after the same has been unlocked.

20 In this modification I have shown the wiping material P' mounted as a roll over a roller 18 suitably journaled in the compartment 15^a of the lid 13^a and from which the wiping material can be fed outwardly under the ledge 16, on slightly 25 lifting the rear lid 13^a.

It is understood that various other modifications may be made in the construction of my suitcase, without departing from the principle of my invention, I, therefore, do not wish to restrict myself to the details described and shown. 30

What I claim is:

1. A suitcase or the like comprising a body formed with a rear compartment for articles of

5 wear and front compartments for bottles or other containers, a lid having top and side walls hinged to the body to cover the rear compartment and a lid having top and side walls hinged to said first lid to cover the front compartments, both said lids being adapted, when closed, to bear with their side walls upon and to be in alinement with one another, said first named lid having a partition formed with a forwardly extending ledge parallel to the top of said lid and 10 serving as shelf for toilet articles.

2. A suitcase according to claim 1, in which the pivotal line of attachment of said two lids coincides with the upper longitudinal edge of said partition, so that when said second lid is opened 15 it will entirely expose said shelf and articles stored thereon.

3. A suitcase according to claim 1, in which the side walls of said rear lid are extended forwardly beyond its said partition and have forwardly slanting edges to form side walls for said shelf. 20

4. A suitcase according to claim 1, in which the front edges of the side walls of said rear lid are slanting, the rear wall of said front lid is omitted and the edges of the side walls of the latter are also slanting so that when the front lid is folded over the rear lid the slanting edges of the two lids will be in linear extension of one another and afford the appearance of a finished 25 dressing cabinet or table. 30
